Primary Examiner — Andrew Kerr*Assistant Examiner* — Chariton Alexakis(74) *Attorney, Agent, or Firm* — Trojan Law Offices(57) **CLAIM**

The ornamental design for an oven, as shown and described.

DESCRIPTION

FIG. 1 is a front perspective view of an oven showing my new design;

FIG. 2 is a back perspective view of the oven of FIG. 1;
FIG. 3 is a left side perspective view of the oven of FIG. 1;
FIG. 4 is a right side perspective view of the oven of FIG. 1;

FIG. 5 is a front view of the oven of FIG. 1;

FIG. 6 is a back view of the oven of FIG. 1;

FIG. 7 is a left view of the oven of FIG. 1;

FIG. 8 is a right view of the oven of FIG. 1;

FIG. 9 is a top view of the oven of FIG. 1; and,

FIG. 10 is a bottom view of the oven of FIG. 1.

The broken lines in the drawings depict portions of the oven that form no part of the claimed design.

1 Claim, 8 Drawing Sheets(56)
